UNITED STATES PATENT OFFICE.

WILLIAM A. DUNLAP, OF PITTSBURG, PENNSYLVANIA.

ATTACHMENT FOR WASHTUBS.

SPECIFICATION forming part of Letters Patent No. 780,876, dated January 24, 1905.

Application filed July 2, 1904. Serial No. 215,054.

To all whom it may concern:

Be it known that I, WILLIAM A. DUNLAP, a citizen of the United States, residing at Pittsburgh, in the county of Allegheny and State of Pennsylvania, have invented or discovered certain new and useful Improvements in Attachments for Washtubs, of which improvements the following is a specification.

As metallic washtubs are necessarily formed with a bead or rim projecting outwardly from their upper edges, considerable difficulty is encountered in securing wringers to the tubs. To this end bearing-pieces have been provided which are secured to the tub immediately below the rim, said pieces being of a thickness which combined with the thickness of the wall of the tub equals or approximately equals the transverse diameter or thickness of the rim.

The object of the present invention is to provide such a bearing-piece as will be capable of being easily attached to and removed from the tubs without changing the usual construction of the latter.

The invention is hereinafter more fully described and claimed.

In the accompanying drawings, forming a part of this specification, Figure 1 is a view in elevation of the upper portion of a tub having my improved bearing piece or block attached thereto. Fig. 2 is a sectional view on a plane indicated by the line II II, Fig. 1. Figs. 3 and 4 are views similar to Fig. 2, illustrating modifications of the improvement.

In the practice of my invention the tub 1 is constructed in the usual or any suitable manner and with a rim or bead 2 around its upper edge. Immediately below this rim or bead are formed openings 3 through the wall of the tub for the passage of supporting-fingers 4 on the bearing-piece block. While this block may be of any form or construction, it is preferred to form it of a transversely-corrugated strip of metal 5, to the rear wall of which are secured the supporting-fingers 4.

These fingers have their ends so constructed that after passing through the openings they

will engage some portion of the tub, so as to prevent accidental displacement. In the construction shown in Fig. 2 the portions of the fingers which pass through the openings are so curved or bent upwardly and outwardly as to lap up onto the curved rim or bead 2. In the construction shown in Fig. 3 the fingers are made in the form of hooks, which will hook into the openings, the ends of the hook bearing against the inner surfaces of the wall of the tub. In Fig. 4 the portions of the fingers passing through the openings are turned upwardly to bear against the wall of the tub above the openings.

It is characteristic of my improvement that the bearing-pieces can be easily and quickly placed in position and that these bearing-pieces can be readily applied to tubs by merely punching holes through the walls below the rims.

I claim herein as my invention—

1. The combination of a tub provided with openings through its side wall and a bearing-piece provided with supporting-fingers adapted to pass through said openings and engage the side wall of the tub, substantially as set forth.

2. The combination of a tub provided with openings through its side wall and a bearing-piece provided with supporting-fingers adapted to pass through said openings and having their ends bent to bear against the inner surface of the wall of the tub, substantially as set forth.

3. The combination of a tub provided with openings through its side wall and a bearing-piece provided with supporting-fingers adapted to pass through said openings and having their ends bent outwardly so as to bear upon the rim of the tub, substantially as set forth.

In testimony whereof I have hereunto set my hand.

WILLIAM A. DUNLAP.
